UNITED STATES PATENT OFFICE.

CHARLES F. GRAY, OF SIERRA MADRE, CALIFORNIA, ASSIGNOR TO THE SINGER MANUFACTURING COMPANY, A CORPORATION OF NEW JERSEY.

SEWING-MACHINE.

1,156,839.

Specification of Letters Patent.

Patented Oct. 12, 1915.

Application filed February 10, 1914. Serial No. 817,737.

To all whom it may concern:

Be it known that I, CHARLES F. GRAY, a citizen of the United States, residing at Sierra Madre, in the county of Los Angeles and State of California, have invented certain new and useful Improvements in Sewing-Machines, of which the following is a specification, reference being had therein to the accompanying drawings.

10. This invention relates to improvements in sewing machines and has for its object to provide an organized machine capable of effecting, at a single operation, both lock-stitch and chain-stitch seams, and for a better understanding of the invention there is herein shown and described a seam structure especially adapted to the manufacture of corsets consisting of three separate parallel seams, the two outer comprising lock-stitches and the inner chain-stitches.

To effect three or more parallel lock-stitch seams by a single operation of an organized machine, as in the earlier constructions, involves disadvantages which increases the cost and limits the design of the product as compared with the present construction, as the means for effecting each of the seams includes an under mass of thread in the form of a small bobbin or cop which must frequently be replaced, and to do this in connection with the stitch-forming mechanism for effecting the central seam calls for complications in construction and of such design as will permit of an exchange of bobbins, and is permissible only in connection with machines employing a comparatively wide needle gage, as there must be sufficient space between the outer loop-takers to permit of the introduction between them of the third or central loop-taker, and to effect even a comparatively wide gage of seams one of the loop-takers must be capable of movement out of its operative position to accommodate the replacing of the central bobbin or mass of thread.

In machines organized to effect three or more parallel lock-stitch seams at a single operation the stitch-forming mechanism is limited, so far as applicant has any knowledge, to the employment of loop-takers operated in a plane corresponding substantially to the line of needle actuation, and while the present invention is applicable to such forms of construction it is more desirable to employ it in connection with loop-takers

having two complete actuations to one complete stitch-forming movement of the needle-carrying bar, the movements of said loop-takers being in a plane which permits of an interchange of bobbins without complications or hindrance due to the formation of the inner or central seam, and in connection with one form of, so termed, universal feed, as in the present construction.

The present invention gives to the manufacturers the advantage of the cheaper and more easily effected chain-stitch seam whenever the product will permit of a multiple seam construction embodying both lock and chain-stitch seams, thus avoiding the employment of the more expensive all lock-stitch three needle seam construction which, it is believed, would if effected by a single operation of an organized machine, be a necessity in the absence of the present construction, and to give to the manufacturers a machine capable of a speed double that of any three-needle lock-stitch sewing machine known to the trade.

It is evident that the present construction might be employed to effect only one of the multiple seams, but such use would simply comprise a possible means, a makeshift or temporary substitute for effecting a given seam, the gist of the invention residing in the providing of means for effecting a seam construction comprising lock-stitch and chain-stitch seams.

Referring to the drawings, Figure 1, is a view in front side elevation of the present sewing machine, the frame being shown partly in section to better illustrate certain details later to be referred to. Fig. 2 an underside view of Fig. 1. Fig. 3 a plan view of the front end portion of the bed-plate; Fig. 3^a the feed-dog shown detached from its actuating mechanism to better illustrate the arrangement of the looper with respect to the loop-takers. Fig. 4 a cross section on the line $x-x$ Fig. 3. Fig. 5 one form of product to which the present machine is especially adapted.

Referring to the figures, 1 represents the sewing machine bed-plate upon which is mounted the bracket-arm comprising the standard 2 and the arm bracket 3, 4 the main or needle-bar driving shaft provided with the band or hand-wheel 5 and operatively connected with the lower or loop-taker actuating shaft 6 by connections, as 7. 110

8 denotes the feed rock-shaft mounted in suitable bearings depending from the bed-plate and at its rear end provided with a crank-arm 9 pivotally connected to the lower end of the feed connection 10, the opposite end of the latter being connected to the main-shaft through a suitable feed eccentric (not shown), thus transmitting from the latter rocking movements to the feed rock-shaft 8. To the front end of the feed rock-shaft is pivotally connected the feed-dog carrying-bar 11 provided with the feed-dog 12, the opposite end of the feed-dog carrying-bar having rigidly secured to it a forked connection 13 which embraces an eccentric 14 carried by the loop-taker actuating shaft, thus transmitting from the latter vertical movements to said feed-dog.

15 represents a needle-feed rock-shaft 20 journaled in suitable bearings formed in the arm bracket and at its rear end provided with a rigidly secured crank-arm 16 to the outer end of which is pivotally connected a needle-feed connection 17, the lower end 25 of the latter being pivotally connected to the crank-arm 9 and having the same axis as the lower end of the connection 10. To the forward end of the needle-feed rock-shaft is suitably secured a needle vibrating 30 arm 18 whose free end enters a suitable slot formed in the collar 19 (shown in dotted lines only, Fig. 1) carried by the needle-bar 20, thus transmitting from the main-shaft through the feed eccentric and connections 35 10, 9, 17, 16, 15, 18 and 19, feed movements to the needles, as 21, corresponding in amplitude to the feed movements of the feed-dog 12. The needle-carrying bar is provided with a needle-carrying-bracket 22 into 40 which is secured the needles 21 and 23 denotes the cloth-presser suitably secured to the lower end 24 of one form of commonly employed cloth-presser carrying bar. The plate 26 secured by screws, as 27, to the front 45 side of the bracket-arm and provided with the index 28, pointer 29 and opening 30 comprise elements forming a part of the feed-adjusting mechanism, but as the latter has no particular bearing on the present invention, further reference to its constructive 50 features is deemed unnecessary.

31 and 32 represent the left and right hand loop-takers respectively, each of which are provided with a non-rotating bobbin case 55 as 33 and each of the latter with thread-bobbins as 34. The bobbin cases being held against rotation by suitable lugs as 35 (one only of which is shown, see Fig. 4) depending from the underside of the throat or 60 needle-plate 36 and entering the notches as 25 formed in said bobbin cases, as in earlier constructions.

37 and 38 denote the loop-taker shafts of loop-takers 31 and 32 respectively, said 65 shafts being journaled in the respective

brackets 39 and 40, said brackets at one edge being secured by pinch-joints, as 41, on the shaft bushings, as 42, the opposite edges of said brackets being held against accidental displacement by screws, as 45, threaded into the bed-plate 1. The loop-takers 31 and 32 are operatively connected with the loop-taker actuating shaft 6 through the spiral-gears 46 and 47, carried by said shaft, acting on the spiral-gears 48 and 49 carried by the respective loop-taker shafts 37 and 38. The ratio of said gears being as one to two, thus giving to the loop-taker two rotations to one complete actuation of the needle-carrying-bar.

50 represents a looper actuating eccentric carried by the loop-taker actuating shaft 6 and encircled by an eccentric strap or collar 51 provided with a bearing 52 inclined to the plane of rotation of said eccentric, and into said bearing is mounted the looper carrying rod 53 provided with the looper 54, the opposite end of said rod being secured by means of the pivot screw 55 in a forked opening 56 of the sliding sleeve 57, which latter is mounted on the pin 58 carried by a bracket 59 secured by screws, as 60, to a stationary part of the sewing machine frame. The looper 54 comprises a straight blade having the usual thread eye at its point, its opposite end being provided with the thread leader 61 through which the looper thread is passed to the thread eye, the eccentric strap or collar 51 being confined between the flanges, as 62, carried by the eccentric 50.

63 denotes a needle thread loop guard carried by the looper between which and said guard the needle rises in the formation of its thread loop the guard acting to better insure the formation of the loop at the side of the needle next the looper.

From the foregoing it will be readily understood that the eccentric 50 transmits to the looper needle, thread loop-engaging and loop-shedding movements in directions transverse to the looper actuating shaft, and that the angularly arranged bearing 52 acts upon the loop-carrier rod 53 to effect needle avoiding movements of the loop-taker in directions corresponding to the length of said shaft. It is not deemed necessary to herein define the relative action of looper and its coacting needle to form stitches, as such relative action is common to earlier constructions and well understood by those versed in the art, except to explain that as the looper is moved toward the front of the machine it enters the needle-thread loop as the needle is being moved upward, the next subsequent descent of the needle entering the looper-thread loop, when the looper in its further movement in a direction away from the front of the machine sheds the needle-thread loop which is drawn into the fabric in the formation of 130

the stitch, during which time the looper has reversed its motion to form a succeeding stitch, the looper being at the left of the needle during its forward movement and at 5 the opposite side during its retracted movement.

Nearly, if not all, chain-stitch stitch-forming mechanisms employ a needle-thread take-up for controlling the slack of the 10 thread after the looper has entered the thread-loop to substantially the completion of the upward stroke of the needle. Such take-up in some varieties of constructions being independent of the needle-bar and in 15 others effected by passing the thread through a suitable opening in the upper end of the needle-bar. In the present construction the like control of the like thread is effected by the downward movement of the lock-stitch 20 take-up 68, which, as is well understood, effects its most important functions of controlling the formation of a lock-stitch seam on its upward movement when, after the 25 loop has been cast about the under cop or bobbin, acts to control the slack of the diminishing loop, and at substantially the completion of such movement acts to set the stitch. In the present construction the 30 lock-stitch seam take-up, in connection with the thread leader 75, effects the same control of the chain-stitch needle thread as the needle-bar or independent take-up common to chain-stitch sewing machine construction.

In the threading of the needles and looper 35 the two lock-stitch needle threads (not shown) are passed from the supply to their respective thread-checks, as 64, tension devices, as 65, thread-control 66, thread eye 67 of the take-up 68, thread leaders, as 69, 40 thread retaining checks, as 70, needle openings, as 71, in bracket 22, and through the respective thread eyes of the outer of the needles 21. The looper needle thread 72 is passed from the supply through the thread 45 eye 73, tension device 74, thread leader 75 formed in the bracket 76 adjustably secured by screws, as 77, to the tension bracket 78, carried by the arm-bracket, beneath the take-up 68, through the thread opening 79, 50 thread retaining check 80, needle opening 81, from which latter it is passed through the eye of the centrally located needle. The looper or under chain-stitch thread 82 is passed first through the tension 83, thread 55 check 83' to the action of the under take-up 84, then through the tubular opening 85 to the thread leader 61 carried by the looper 54, and through the thread eye 86 of said 60 looper.

The present looper-actuating mechanism is adapted for either the eyed or non-eyed looper, dependent upon whether a single or double chain-stitch is desired.

The introduction of Fig. 5 into the 65 present application is for a better under-

standing of the advantages of the present invention for manufacturing purposes. Referring to the figure, the corset-steel or stay pockets, as 87, for the stays, as 88, are formed by stitching the strip 89 to the 70 body portion 90 by three parallel seams effected at a single operation by an organized machine, and until after the introduction to the trade of the present construction each of the seams were composed of either 75 lock or chain-stitches, the latter being employed in connection with poorer or cheaper grades of corsets and the former in connection with the manufacture of the better grades, the employment of the three lock- 80 stitch seams in the latter grades being a necessity as there were no machines known to the trade capable of effecting the inner chain-stitch seam *a* in connection with the outer lock-stitch seam *b* and *c* at a single 85 operation, as herein. It is well understood that a chain-stitch seam positioned so that the exposed portions of the thread are protected against severe wear, as is the lock-stitch seam *a* by the pockets 87 and stays 90 88, is as durable as the lock-stitch seam and more desirable in the matter of cost and convenience of operation, and accordingly, whenever such combination of seam construction is permissible the cost is materially 95 reduced and convenience of operation simplified.

Having thus set forth the nature of the invention, what I claim herein is:—

1. In an organized sewing machine for 106 effecting at a single operation a seam construction including a lock-stitch and a chain-stitch seam, the combination with a single needle-bar provided with a multiple of needles of a chain-stitch looper and rotary 105 loop-takers, the latter provided with a mass of under thread.

2. In a sewing machine, the combination with a plurality of reciprocating needles, of 110 circularly-moving loop-takers coöperating with two of said needles and formed with thread cavities containing masses of lower thread embraced by the paths of movement of their respective beaks, and a chain-stitch looper having a needle-loop detaining blade 115 coöperating with another of said needles intermediate said loop-takers.

3. In an organized sewing machine for effecting at a single operation a seam construction including a lock-stitch and a chain-stitch seam, the combination with multiple needles, of a chain-stitch looper having one complete actuation to one complete action of its coacting needle and a rotary loop-taker, the latter provided with a mass of under 120 thread and having a multiple of complete actuations to one complete action of its co-acting needle.

4. In an organized sewing machine for 125 effecting at a single operation a seam con- 130

struction including a lock-stitch and a chain-stitch seam, the combination with a single needle-bar provided with a multiple of needles, an upper main-shaft, a loop-taker, 5 a loop-taker actuating shaft provided with an eccentric, of a chain-stitch looper and looper carrier, the latter operatively connected with said eccentric.

5. In an organized sewing machine for 10 effecting at a single operation a seam construction including a lock-stitch and a chain-stitch seam, the combination with an upper main-shaft, a needle-bar provided with a threaded needle for effecting a chain-stitch 15 seam and a threaded needle for effecting a lock-stitch seam, a lower looper actuating shaft, and a chain-stitch looper and a loop-taker each provided with an under thread, of an under thread take-up operatively connected with said latter shaft and an upper thread take-up operatively connected with 20 said main-shaft, the former take-up acting to control the chain-stitch looper thread and the upper take-up the sewing threads for 25 effecting the lock-stitch seam, the downward movement of the latter take-up also acting

to control the formation of the chain-stitch seam.

6. In an organized sewing machine for 30 effecting at a single operation a seam construction including a lock-stitch and a chain-stitch seam, the combination with an upper main-shaft, a needle-bar provided with a threaded needle for effecting a chain-stitch seam and a threaded needle for effecting a 35 lock-stitch seam, a lower looper actuating shaft, a chain-stitch looper and a loop-taker, the latter provided with a mass of under thread, of a needle thread take-up operatively connected with said main-shaft and 40 acting to control the sewing thread for effecting the lock-stitch seam, the downward movement of said take-up acting to control the formation of the chain-stitch seam.

In testimony whereof, I have signed my 4 name to this specification, in the presence of two subscribing witnesses.

CHARLES F. GRAY.
